SCHEIN, OF VARCHMIN, KREIS KOSLIN, GERMANY

CULTIVATOR

Original application filed December 27, 1924, Serial No. 758,466, and in Germany March 10, 1924. Divided
and this application filed January 19, 1928. Serial No. 247,989.

My invention relates to cultivators, and has particular relation to the provision of means in connection with such apparatus as will insure the proper operation of the same when various obstructions, such as stones, etc., are encountered as the tools of the machine move over and through the surface of the ground.

Cultivators are at present used in which the tool shaft is rotating, to said shaft being secured resiliently swinging tools. When an obstruction is encountered and a predetermined pressure is thereby exceeded at the point of the tool, the tools yield resiliently about their suspension points and initiate a movement of the obstruction or stone forwardly in the direction that the tools move about their suspension points.

If coil springs are made to act on the tools, these springs, which also serve as a link to pivotally and resiliently support the tools on the shaft, are distorted by the pressure exerted by the points of the tools upon the stones or other obstructions, radial forces acting on the springs, whereby the compressed steel fibres of the springs are liable to be overstrained and breakage of the spring may occur. It is therefore important that means be provided whereby the coil springs (this term being intended throughout this specification and the appended claims to include spiral springs of all kinds it being understood that such springs are arranged with their coils clear of obstructions, as and for the purpose described) on the shaft, such springs are arranged with their axis substantially in parallel relation with the axis of the shaft, and the coils of the springs are clear of all adjacent parts so that they cannot get into frictional contact with such parts when the springs are subjected to, or relieved from, tension, whereby wear and eventual failure of the spring wire are prevented. Springs arranged with their coils clear of obstructions but in the usual manner, are distorted by the pressure or tension exerted, are

nevertheless free to contract and expand substantially in their natural path.

This is obtained, according to the present invention, by providing an abutment for the top portion of the tool, so that this end of the tool is prevented from exerting any undue radial pressure on the spring or springs supporting the tool, such pressure being taken up by the said abutment, which, in the preferred embodiment of my invention, has the form of a crank arm fixed on the shaft, the free end of which extends into the axial line of the supporting spring or springs and has the top end of the tool hinged to it.

In the drawings affixed to this specification and forming part thereof a device embodying my invention is illustrated diagrammatically by way of example.

In the drawings

Figure 1 is a side elevational view showing the parts in their normal position.

Figure 2 is a similar view of the same parts after they have encountered an obstruction.

Fig. 3 is a rear view.

Referring to the drawings 1 is a tool shaft of a cultivator, 22, 23 and 24 are arms projecting for one side of the shaft and pitched apart axially as shown in Fig. 3, 7 is a pivot inserted in the central arm 23 in the axis of a pair of juxtaposed coil springs 11 the inner ends 12-12 of each spring being secured to the tool 3, as shown, while the outer ends 13-13 are secured to the arms 22 and 24 respectively, of the shaft 1. The springs 11 thus support the tool, the top end of which is hinged to the crank arm at 7.

When the free end 6 of the tool encounters an obstruction, the ends 12 and 13 of each spring approach one another by describing approximately a circle about the pivot 7. They cannot, however, depart radially from the circle because the pivot 7 absorbs the excessive radial strains, and does

not yield when the point 6 of the tool strikes against a stone 8 and tends to rise.

Fig. 1 shows the tool 3 just before its end 6 strikes the stone 8 which is on the ground 15. The line X—X extending from the axis of the shaft 1 to the axis of the pivot 7, and the line a—b which extends from the end 6 of the tool 3 to the axis of the pivot 7, include an obtuse angle, in the initial position of the parts, with its apex in the pivot 7. The force which is exerted by the tool 3 tends to throw over the stone and the reaction tends to move the tool 3 out of the vertical position shown in Fig. 1 but due to the obtuse angle at the pivot 7 in combination with the rotary shaft 1, the arm 23 does not move the tool out of its vertical position but only raises it as shown in Fig. 2. If the tool is not able to throw over the stone 8 by tilting it about its rear support on the ground 15, the tool rapidly rises further, while its end 6 slides across the stone while the obtuse angle illustrated in Fig. 1 is changed into a more acute angle by the force exerted at the shaft 1.

While I have described my invention in detail as to the actual construction employed, it is obvious that many modifications therein may occur to those skilled in the art, and I desire, therefore, that my invention be limited only by the showing of the prior art, or by the scope of the appended claims.

I claim:—

1. A cultivator comprising a shaft, a coil spring with its coils clear of obstructions, and with its axis arranged substantially in parallel relation with respect to the axis of said shaft, said spring being connected with said shaft at one end, a tool connected with the other end of said spring, and an arm extending from said shaft to said tool so as to form an abutment for said tool and to prevent radial distortion of the free coils of said spring when the end of said tool engages an obstacle.

2. A cultivator comprising a shaft, a coil spring with its coils clear of obstructions, and with its axis arranged substantially in parallel relation with respect to the axis of said shaft, said spring being connected with said shaft at one end, a tool connected with the other end of said spring, and an arm extending from said shaft to said tool, the free end of said arm being connected with said tool by a pivot so as to prevent radial distortion of the free coils of said spring when the end of said tool engages an obstacle.

3. A cultivator comprising a shaft, a coil spring with its coils clear of obstructions, and with its axis arranged substantially in parallel relation with respect to the axis of said shaft, said spring being connected with said shaft at one end, a tool connected with the other end of said spring, and an arm ex-

tending from said shaft to said tool, the free end of said arm being connected with said tool by a pivot in the axis of said spring so as to prevent radial distortion of the free coils of said spring when the end of said tool engages an obstacle.

4. A cultivator comprising a shaft, two coil springs with their coils clear of obstructions and with their axes arranged substantially in parallel relation with respect to the axis of said shaft, said springs being connected with said shaft at one of their ends, a tool connected with the other ends of said springs, and an arm extending from said shaft to said tool so as to form an abutment for said tool and to prevent radial distortion of the free coils of said springs when said tool engages an obstacle.

5. A cultivator comprising a shaft, two coil springs with their coils clear of obstructions and with their axes arranged substantially in parallel relation with respect to the axis of said shaft, said springs being connected with said shaft at one of their ends, a tool connected with the other ends of said springs, and an arm extending from said shaft to said tool, the free end of said arm being connected with said tool by a pivot, so as to prevent radial distortion of the free coils of said springs when said tool engages an obstacle.

6. A cultivator comprising a shaft, two coil springs with their coils clear of obstructions and with their axes arranged substantially in parallel relation with respect to the axis of said shaft, said springs being connected with said shaft at one of their ends, a tool connected with the other ends of said springs, and an arm extending from said shaft to said tool, the free end of said arm being connected with said tool by a pivot in the axis of said springs, so as to prevent radial distortion of the free coils of said springs when said tool engages an obstacle.

7. A cultivator comprising a shaft, two coil springs with their coils clear of obstructions and with their axes arranged substantially in parallel relation with respect to the axis of said shaft, said springs being connected with said shaft at one of their ends, a tool connected with the other ends of said springs, and an arm extending from said shaft to said tool, the free end of said arm being connected with said tool by a pivot in the axis of said springs, and centrally intermediate said springs, so as to prevent radial distortion of the free coils of said springs when said tool engages an obstacle.

8. A cultivator comprising a shaft, a coil spring with its coils clear of obstructions, and with its axis arranged substantially in parallel relation with respect to the axis of said shaft, said spring being connected with said shaft at one end, a tool connected with the other end of said spring, and an arm ex-

tending from said shaft to said tool so as to form an abutment for said tool, with a line connecting the axis of said spring with the axis of said shaft, and a line connecting the

5 axis of said spring with the end of said tool, said lines including an obtuse angle the apex of which is in the axis of said spring, when said tool is in its initial position, so as to enable the end of said tool to move rapidly

10 across an obstacle which it cannot remove.

9. A cultivator comprising a shaft, a coil spring with its coils clear of obstructions, and with its axis arranged substantially in parallel relation with respect to the axis of

15 said shaft, said spring being connected with said shaft at one end, a tool connected with the other end of said spring, and an arm ex-

tending from said shaft to said tool, the free end of said arm being connected with said

20 tool by a pivot, with a line connecting the axis of said pivot with the axis of said shaft, and a line connecting the axis of said pivot with the end of said tool, said lines including an obtuse angle the apex of which is in the

25 axis of said pivot, when said tool is in its initial position so as to enable the end of said tool to move rapidly across an obstacle which it cannot remove.

10. A cultivator comprising a shaft, two coil springs with their coils clear of obstruc-

tions and with their axes arranged substan-

tially in parallel relation with respect to the axis of said shaft, said springs being connected with said shaft at one of their

30 ends, a tool connected with the other ends of said springs, and an arm extending from said shaft to said tool so as to form an abutment for said tool with a line connecting the axis of said springs with the axis of said shaft,

35 and a line connecting the axis of said springs with the end of said tool, said lines including an obtuse angle, the apex of which is in the axis of said springs, when said tool is in its initial position, so as to enable the end of

40 said tool to move rapidly across an obstacle which it cannot remove.

11. A cultivator comprising a shaft, two coil springs with their coils clear of obstruc-

tions and with their axes arranged substan-

50 tially in parallel relation with respect to the axis of said shaft, said springs being connected with said shaft at one of their ends, a tool connected with the other ends of said springs, and an arm extending from said shaft

55 to said tool, the free end of said arm being connected with said tool by a pivot, with a line connecting the axis of said pivot with the axis of said shaft, and a line connecting the axis of said pivot with the end of said tool,

60 said lines including an obtuse angle the apex of which is in the axis of said pivot, when said tool is in its initial position so as to enable the end of said tool to move rapidly across an obstacle which it cannot remove.

65 12. A cultivator comprising a shaft, a coil

spring with its coils clear of obstructions and with its axis arranged substantially in parallel relation with respect to the axis of said shaft, said spring being connected with said shaft at one end, a tool secured to the other end of

70 said shaft, an arm extending from said shaft to said tool, a pivot connecting the free end of said arm and said tool in the axis of said

75 spring, with a line connecting the axis of said pivot with the axis of said shaft, and a line

80 connecting the axis of said pivot with the end of said tool, said lines including an obtuse angle the apex of which is in the axis of said pivot, when said tool is in its initial position so as to enable the end of said tool to move

85 rapidly across an obstacle which it cannot remove.

13. A cultivator comprising a shaft, two coil springs with their coils clear of obstruc-

85 tions and with their axes arranged substan-

tially in parallel relation with respect to the axis of said shaft, said springs being connected with said shaft at one of their ends, a

90 tool connected with the other end of said spring, an arm extending from said shaft to

95 said tool, and a pivot connecting the free ends of said arm and said tool, said pivot being ar-

99 ranged centrally intermediate said springs, and in their axial line, with a line connecting the axis of said pivot with the axis of said

100 shaft, and a line connecting the axis of said pivot with the end of said tool, said lines including an obtuse angle the apex of which is in the axis of said pivot, when said tool is in its initial position so as to enable the end

105 of said tool to move rapidly across an obstacle which it cannot remove.

14. A cultivator comprising a shaft, a coil spring with its coils clear of obstructions and with its axis arranged substantially in par-

110 allel relation with respect to the axis of said shaft, said spring being connected with said shaft at one end, a tool connected with the other end of said spring, an arm on said tool,

115 and an abutment on said shaft for the free end of said arm so as to prevent radial dis-

120 tortion of the free coils of said spring when the end of said tool engages an obstacle.

15. A cultivator comprising a shaft, a coil spring with its coils clear of obstructions and with its axis arranged substantially in par-

125 allel relation with respect to the axis of said shaft, said spring being connected with said shaft at one end, a tool connected with the

other end of said spring, an arm on said tool,
an arm on said shaft, and a pivot connecting
said arms, with a line connecting the axis of
said pivot with the axis of said shaft, and a
line connecting the axis of said pivot with the
end of said tool, said lines including an obtuse
angle the apex of which is in the axis of said
pivot, when said tool is in its initial position
so as to enable the end of said tool to move
rapidly across an obstacle which it cannot
remove.

In witness whereof, I have hereunto sub-
scribed my name.

WILHELM GRAMS.
